(57) **CLAIM**

I claim the ornamental design for an outer shell of a helmet for a hockey or lacrosse player, as shown and described.

DESCRIPTION

FIG. 1 is a front side perspective view of an outer shell of a helmet for a hockey or lacrosse player according to the present design;

FIG. 2 is a rear side perspective view thereof;

FIG. 3 is a front elevational view thereof;

FIG. 4 is a rear elevational view thereof;

FIG. 5 is a right side elevational view thereof;

FIG. 6 is a left side elevational view thereof; and,

FIG. 7 is a top plan view thereof.

The broken lines showing is included for the purpose of illustrating environment and forms no part of the claimed design.
